CLAIM

The ornamental design for a merchandise display rack,
as shown and described.

DESCRIPTION

FIG. 1 is a perspective view of a merchandise display
rack showing my new design;

FIG. 2 is a front elevational view thereof;

FIG. 3 is a left side elevational view, the right side being
a mirror image thereof; and

FIG. 4 is a top plan view thereof.

The rear of the merchandise display rack is substantially
flat and unornamented.

Fig. 2.

Fig. 4.

Fig. 1.

Fig. 3.
